[57] CLAIM

I claim the ornamental design for a pocketknife, as shown and described.

DESCRIPTION

FIG. 1 is a perspective view of a pocketknife with its blade shown in a folded position;
FIG. 2 is an enlarged tip end view thereof;
FIG. 3 is an enlarged hinge end view thereof;
FIG. 4 is a bottom plan view thereof;
FIG. 5 is a front elevational view thereof;
FIG. 6 is a top plan view thereof;
FIG. 7 is a back elevational view thereof; and,
FIG. 8 is a perspective view of the pocketknife of FIG. 1, with its blade shown in an alternate, extended position.
